Primary Examiner — Mary Ann Calabrese*(74) Attorney, Agent, or Firm* — Christensen O'Connor Johnson Kindness PLLC(57) **CLAIM**

The ornamental design for a blind slat, as shown and described.

DESCRIPTION

1. Blind slat

1.1 is a top view;

1.2 is a bottom view;

1.3 is a front view, the rear view is a mirror image thereof;

1.4 is a right side view, the left side view is a mirror image thereof;

1.5 is an enlarged fragmentary top view of the slat showing the hole;

1.6 is an enlarged fragmentary bottom view of the slat showing the hole;

1.7 is a cross-sectional right view, through middle of the slat through the hole of view 1.5; and,

1.8 is a cross-sectional front view, through middle of the slat through the hole of view 1.5.

The evenly spaced broken lines represent features that from no part of the claimed design. The dot-dash broken lines represent a symbolic break in the length. The appearance of any portion of the article between the break lines forms no part of the claimed design.

1 Claim, 8 Drawing Sheets(56)
